APPARATUS FOR MAKING U-SHAPED
BRAKE HANGERSFrederic Schaefer, Pittsburgh, Pa., assignor to
Schaefer Equipment Company, Pittsburgh, Pa.,
a corporation of Pennsylvania

Application April 7, 1950, Serial No. 154,610

5 Claims. (Cl. 153—35)

1

This invention relates to the manufacture of U-shaped brake hangers which suspend brake beams from the trucks of railroad cars.

A common way of manufacturing U-shaped brake hangers is first to heat and upset one end of a round rod to form a thickened portion which is punched to provide one eye for the hanger. The opposite end of the rod is heated, upset and punched to form the other eye. The rod then is reheated and bent into a loop having parallel legs connected by an outwardly curving yoke-forming member. Next, suitable dies move the legs away from each other and straighten the yoke-forming member. Following this, the hanger is again reheated and forced to cause the metal at the yoke corners of the hanger to flow outwardly to form strengthening ribs. Finally, the hanger is reheated and oil quenched.

Although hangers produced by the above method are, in most cases, satisfactory, some of them have been found to be weakened at their yoke corners. This is due to the fact that the separate step of forging the corners to form the strengthening ribs sometimes sets up strains therein and eventually may cause the corners to crack. Also, the bending of the original straight rod at 90 degrees may overstress it. Some difficulty also is encountered in making the legs of the hanger exactly the same length and perfectly straight and parallel without deforming the hanger eyes. Another drawback to such a method of making hangers lies in the necessity for numerous heats before the product is finished. In the method outlined above, at least four heats are required, which increase the time and number of workmen required for the job. Consequently, the cost of the product likewise is increased.

It is among the objects of this invention to provide apparatus for manufacturing U-shaped brake hangers, for which less heats are required than heretofore, and which produces stronger and more accurately formed hangers. Another object is to provide apparatus for stretching a U-shaped hanger blank to correct size without injuring it.

In accordance with this invention, a metal bar is heated to forging temperature and then forged to form a narrow blank having spaced side members connected at one end by an outwardly curved end member, and having at the opposite end flattened portions of increased width which later will be provided with aligned pin-receiving openings. The flattened portions lie in substantially parallel planes and project from opposite sides of the legs. At the same time that the bar is forged, the portions of the blank where its side members join the curved end member are thickened in the plane of the blank, such as by forging ribs on the outside of the blank. After the forging operation, the flash is trimmed from the blank, and

then the side members are spread farther apart to form hanger legs and to simultaneously straighten the end member a considerable extent to form a yoke. Pressure is then applied in opposite directions to the inner surface of the yoke and to the yoke end of the flattened portions of the blank in order to stretch and straighten the legs and simultaneously complete the straightening of the yoke. All hangers thus are made the same length and are provided with straight parallel legs. Openings then can be punched or drilled in the flattened portions of the hanger to complete the eyes of the hanger, by which the hanger is suspended in a car truck.

The invention is illustrated in the accompanying drawings, in which Fig. 1 is a side view of a narrow hanger blank after the initial forging operation; Fig. 2 is a side view of the trimmed blank spread out wider; Fig. 3 is a side view of the blank-stretching apparatus; Fig. 4 is a vertical section thereof, taken on the line IV—IV of Fig. 3; Fig. 5 is a view similar to Fig. 3, but showing the blank stretched; and Fig. 6 is a plan view of the apparatus as shown in Fig. 5.

Referring to Fig. 1 of the drawings, a suitable body of metal, such as a short heavy rod (not shown), is heated to a forging temperature and then forged between suitable dies to form a narrow blank having parallel side members 1 connected at one end by an outwardly curved end member 2. At the junctures of the side members with the end member, outside strengthening ribs 3 are formed at the same time. During this same forging operation the other ends of the side members are provided with wide flattened portions 4 that project in parallel planes from the opposite sides of the legs. These portions have flat inner and outer surfaces, and curved side surfaces that merge into the side members. These flattened portions are needed in order to provide sufficient metal for the hanger eyes that are formed later. The usual flash 5 surrounds the forged blank and fills the space between the side members.

Following this forging operation, the flash metal is trimmed away and then the side members 1 are spread farther apart in a suitable spreading machine which is illustrated schematically by the spreading tools 6 in Fig. 2. The side members, which now become hanger legs, are held more or less parallel, and the previously curved end member 2 is straightened to a large extent and becomes a hanger yoke. Relatively sharp corners are formed where the end member joins the side members, and ribs 3 extend around the outside of these two corners to strengthen them. The spread blank then is placed in the machine shown in Figs. 3 to 6 to stretch the legs and to complete the straightening of the yoke.

The hanger stretching machine includes a base plate 10 which is mounted rigidly on any suitable

machine bed (not shown). The top of the plate is provided with a narrow raised surface 11 extending lengthwise of it along its center. On opposite sides of this surface at the front of the plate there are upright guide walls 12 integral with the plate. Near the rear end of the support is another pair of guide walls 13. Slidably mounted on raised surface 11 and against the inner faces of the guide walls is a rectangular bar 14. The bar projects behind the rear end of the plate and there has a thicker and wider head 15 that is guided between a pair of brackets 16 that are secured to the top of the base plate and project behind it. The front end of the slide bar is held down on the plate by a cross member 17 bolted to the front guide walls 13, which have upwardly projecting portions engaging the front side of the cross member.

The slide bar 14 normally is held in its retracted or rear position by coil springs 20 mounted on horizontal rods 21. The front ends of these rods are anchored in blocks 22 mounted on the front portion of the base plate, and the rear ends of the rods extend slidably through an angle bar 23 that extends across the plate and fits against the front and upper surfaces of the head 15. The angle bar is notched to fit down over the slide bar, and is secured to its head by means of a screw 24. The coil springs are compressed between the blocks and this angle bar, so as to urge the latter back toward brackets 16. The slide bar is moved forward periodically on the base plate by any suitable means. For the sake of illustration only, a rotatable cam 25 is shown engaging the rear end of the bar head for pushing the slide bar forward.

Rigidly mounted on top of the rear guide walls 13, and extending across the top of the slide bar in engagement with it, is a stationary clamping block 27. This block is provided at its opposite sides with laterally projecting ledges 28 which help to support the legs 1 of a hanger blank lying on its side above the slide bar. The rear part of each ledge is cut away and its rear surface 29 is inclined down to a shallow recess in the underlying guide wall, whereby a depression 30 is formed for receiving the lower part of one of the flattened portions 4 of the hanger blank. Rear surface 29 of the ledge is shaped to fit as snugly as possible against the adjoining side surface of the flattened portion. The ledge-engaging surface of the flattened portion is at the end of that portion nearest the yoke, often referred to in the claims herein as the yoke end of the flattened portion. A movable die 32, astraddle of the slide bar in front of clamping block 27, is rigidly mounted on the bar and is provided with laterally projecting ledges 33 for supporting the front part of the hanger blank. The front of this die is provided with a straight recess 34 adapted to engage the inner surface of the hanger yoke.

It will be seen that when the slide bar is moved ahead in Fig. 3, the die 32 carried by it will engage the yoke of the hanger blank straddling the die and move the hanger bodily forward until its flattened portions 4 are pulled into depressions 30 in the stationary clamping block and against inclined ledge surfaces 29. To hold the hanger legs down on ledges 28 so that the flattened portions will stay down in depressions 30, a movable clamping element 36 is provided. This element extends entirely across the clamping block 27 and is pivotally mounted in the front ends of a pair of rocker arms 37 whose central portions are mounted on a horizontal pivot pin 38. This pin ex-

tends through the upper part of a support 39 integral with the rear end of the stationary clamping block and projecting above it. The rear ends of the rocker arms carry a horizontal roller 41 which rolls on a cam 42 that is rigidly mounted on angle bar 23 and the head of the slide bar for reciprocation with them. The thin front part of the cam slides in a slot 43 extending through support 39. The movable clamping element 36, which is long enough to overlie the upper sides of the horizontal hanger legs, is shaped to conform to the adjoining upper surfaces of flattened portions 4 at their yoke ends. To permit the clamping element to be moved down onto the hanger blank, the stationary clamping block 27 is provided with a transverse recess 44. The front wall of the recess is engaged by the front side of the movable clamping element when the latter is in clamping position. The portion of the clamping block in front of the recess thus forms a solid abutment for the movable element, which will prevent any movement of the latter during the stretching operation. When the slide bar is in retracted position, the roller 41 rests on the lower part of the cam, because the front ends of the rocker arms are swung upward by a coil spring 45 which connects the movable clamping element to a bracket 46 mounted on top of support 39.

In using this stretching machine the hanger blank, which has been formed as shown in Figs. 1 and 2, is laid on its side on ledges 28 and 33 as shown in Figs. 3 and 4. At this time slide bar 14 is retracted so that flattened portions 4 of the blank can be inserted under the raised clamping element 36, and yoke 2 can be placed in front of movable die 32. The slide bar then is moved forward to carry the die forward. As soon as the front end of the die engages the inner surface of the hanger yoke the hanger is moved bodily forward, sliding on ledges 28. As the bar continues to move forward the cam 42, which also is carried by it, raises the rear ends of rocker arms 37. This swings clamping element 36 down into recess 44 of clamping block 27 and presses the upper clamping element against the top of the hanger legs. The hanger legs continue to be pulled forward between the two clamping members until the yoke ends of flattened portions 4 engage element 36 and clamping block surfaces 29 in depressions 30. This engagement prevents any further forward movement of the flattened portions, but the slide bar has not yet completed its full forward stroke. The further short distance that it then travels causes die 32, which is pushing forward against the yoke of the hanger blank, to stretch hanger legs 1. This stretching also straightens the legs and makes them parallel and the same length. Just before the forward stroke of die 32 is completed, it pushes the yoke into a recess 47 of a stationary die 48 bolted to guide walls 12 directly in front of cross member 17. When the two dies come together in this manner the yoke 2 of the hanger blank is forged between them into a perfectly straight member. As soon as slide bar 14 is moved back to its rear position by means of springs 20, the forged and stretched hanger can be pulled out of die 48 and lifted from the machine. It is then ready to have eyes formed in flattened portions 4. Because these flattened portions are solid at the time of the stretching of the hanger, there is no danger of deforming the eyes, which have not yet been formed. All hangers stretched in this machine are provided with straight, parallel legs of uni-

form length, and their yokes are straightened and shaped properly.

According to the provisions of the patent statutes, I have explained the principle of my invention and have illustrated and described what I now consider to represent its best embodiment. However, I desire to have it understood that, within the scope of the appended claims, the invention may be practiced otherwise than as specifically illustrated and described.

I claim:

1. Apparatus for stretching a U-shaped brake hanger blank having laterally spaced legs connected at one end by a yoke and having at their opposite end flattened portions of increased width lying in substantially parallel planes, said apparatus comprising a support, a bar slidable lengthwise thereon, a member mounted on the bar for engaging the inner surface of the yoke of said hanger when the hanger is laid on its side above the bar, a stationary clamping element mounted on the support behind said member and provided with depressions for receiving the lower parts of said flattened portions of the hanger, a rocker arm above the bar, means on said support pivotally supporting the arm on an axis transverse to the bar, a movable clamping element carried by the front end of the arm, and a cam carried by the bar behind the arm and adapted to lift the rear end of the arm while the bar is moving forward, whereby to press the movable clamping element down on the hanger before said member pushes the yoke far enough forward to stretch the hanger legs.

2. Apparatus for stretching a U-shaped brake hanger blank having laterally spaced legs connected at one end by a yoke and having at their opposite end flattened portions of increased width lying in substantially parallel planes, said apparatus comprising a support, a bar slidable lengthwise thereon, a member mounted on the bar for engaging the inner surface of the yoke of said hanger when the hanger is laid on its side above the bar, a stationary clamping element mounted on the support behind said member and provided with depressions for receiving the lower parts of said flattened portions of the hanger, a pair of laterally spaced rocker arms above the bar, means on the support between the arms pivotally supporting their central portions on an axis extending transversely of the bar, a movable clamping element connecting the front ends of the arms, a roller connecting the rear ends of the arms, a cam carried by the bar behind said roller and adapted to lift the roller while the bar is moving forward, whereby to press the movable clamping element down on the hanger legs before said member pushes the yoke far enough forward to stretch the hanger legs, and means for reciprocating said bar lengthwise.

3. Apparatus for stretching a U-shaped brake hanger blank having laterally spaced legs connected at one end by a yoke and having at their opposite end flattened portions of increased width lying in substantially parallel planes, said apparatus comprising a support, a bar slidable lengthwise thereon, a member mounted on the bar for engaging the inner surface of the yoke of said hanger when the hanger is laid on its side above the bar, a stationary clamping element mounted on the support behind said member and provided with depressions for receiving the lower parts of said flattened portions of the hanger, a pair of laterally spaced rocker arms

above the bar, means between the arms pivotally supporting their central portions on an axis extending transversely of the bar, a movable clamping element connecting the front ends of the arms, a roller connecting the rear ends of the arms, a cam carried by the bar behind said roller and adapted to lift the roller when the bar is moved forward, whereby to press the movable clamping element down on the hanger legs before said member pushes the yoke far enough forward to stretch the hanger legs, a rotatable cam engaging the rear end of said bar for periodically moving the bar forward, and resilient means constantly urging the bar backward and holding it against said rotatable cam.

4. Apparatus for stretching a U-shaped brake hanger blank having laterally spaced legs connected at one end by a yoke and having at their opposite end flattened portions of increased width lying in substantially parallel planes, said apparatus comprising a support, a die rigidly mounted on the support, a member behind the die and movable forward toward it for engaging the inner surface of the yoke between them, a stationary clamping member mounted on said support behind said movable member, a movable clamping member mounted on the support for movement toward the stationary clamping member to hold said flattened portions, means movably mounted on said support for moving said yoke-engaging member forward toward said die to straighten the yoke against it, and means actuated by said first-mentioned means during its forward movement for moving said movable clamping member toward the stationary clamping member to hold said flattened portions.

5. Apparatus for stretching a U-shaped brake hanger blank having laterally spaced legs connected at one end by a yoke and having at their opposite end flattened portions of increased width lying in substantially parallel planes, said apparatus comprising a support, a die rigidly mounted on the support, a member behind the die and movable forward toward it for engaging the inner surface of the yoke between them, a stationary clamping member mounted on said support behind said movable member, a movable clamping member normally spaced from the stationary clamping member and movable toward it to hold said flattened portions, a rocker arm mounted on said support and supporting said movable clamping member, means movably mounted on the support for moving said yoke-engaging member forward toward said die to straighten the yoke against it, and a cam carried by said means for rocking the arm while said means is moving forward, whereby to move said movable clamping member toward the stationary clamping member to hold said flattened portions.
